UNITED STATES PATENT OFFICE

2,351,517

TURBOTRANSMISSION

Joseph Jandasek, Detroit, Mich., assignor to Bendix Aviation Corporation, South Bend, Ind., a corporation of Delaware

Application November 25, 1940, Serial No. 366,949

8 Claims. (Cl. 103—115)

This invention relates to transmissions and more particularly to fluid transmissions which transmit power from one shaft to another through a circulating liquid.

An object of this invention resides in the provision of fluid directing blades or vanes designed and proportioned in such a manner as to impart to or absorb maximum energy from a circulating liquid by rotatable impeller or turbine members.

Another object of the invention is to provide fluid directing vanes of efficient fluid foil shape which accurately conform to the contour of the fluid circulating passages of the device.

A further object of the invention resides in the provision of fluid directing vanes of efficient fluid foil shape designed in such a manner that their center lines correspond with the theoretical center lines of a power transmitting circulating liquid in the turbopower transmitter.

A still further object is to provide a turbine blade design for a fluid transmission wherein a fluid foil shaped blade of efficient design is contoured in such a manner that its theoretical center line accurately corresponds to the theoretical maximum efficiency flow curves of the turbo-device operating with substantially predetermined entrance and discharge angles.

Yet a still further object is to form a turbine vane from an efficient fluid foil shaped member wrapped around a conical curve such for example as a parabola or hyperbola to provide an efficient turbine energy absorbing vane.

Still another object of the invention resides in the provision of efficient impeller blades generated by wrapping the theoretical axis of fluid foil shaped contours around involute curves to provide impeller blades shaped to transmit energy to liquid in the most efficient manner.

Another object of the invention resides in the provision of impeller blades of efficient fluid foil shape having theoretically substantially straight center lines for a major portion of their length and curved center lines to vary the fluid energizing characteristics of the blade adjacent the trailing edge and wherein the entire impeller blade is wrapped around an involute curve corresponding in shape to the contour of the impeller channel of the turbotransmission.

A further object of this invention is to provide an impeller fluid energizing blade having a contoured form so proportioned that energy may be transmitted to a circulating medium throughout the major length of the blade and wherein the trailing edge of the blade is contoured angularly in such a manner that substantially no energy is

imparted to the circulating liquid as the liquid leaves the impeller blades thereby equalizing fluid pressure over the entire discharge area of the impeller.

Other objects and advantages of this invention will be apparent from the following detailed description considered in connection with the accompanying drawing, submitted for purposes of illustration only, and not intended to define the scope of the invention, reference being had for that purpose to the subjoined claims.

In the drawing wherein similar reference characters refer to similar parts throughout the several views:

15 Fig. 1 is a side elevational view of a device embodying the present invention and illustrating the impeller blade and turbine vanes.

20 Fig. 2 is a sectional view taken substantially on the line 30a of Fig. 1, showing the first stage turbine vane 18 having a straight center line 30 before it is bent.

25 Fig. 3 is a view similar to Fig. 2 taken substantially on the line 30a of Fig. 1 of the same vane after its center line 30 has been bent to form a conical curve 30b of two-dimensional form.

30 Fig. 4 is a section through the second stage turbine vanes 18 taken on the line 40a of Fig. 1 illustrating the vane in the two-dimensional form as if the center line 40a of Fig. 1 were a straight line.

Fig. 5 is a side view of the vane 18 looking axially from the discharge end.

35 Fig. 6 is a view similar to Fig. 1 looking in the opposite direction representing the vane 18 as if all points of the vane were turned in one plane. This view represents one step in laying out the vane.

40 Fig. 7 illustrates a two-dimensional impeller blade 20 having approximately a 45° pitch angle to the direction of rotation throughout except at the tail end of the blade.

45 Fig. 8 is a three-dimensional view of the blade 20 wrapped around an involute curve. Profile 54 represents the same blade as in Fig. 7 having a pitch angle of approximately 45° in the portion adjacent the web, and a profile 53 adjacent the shroud of a pitch angle of approximately 30°.

50 Fig. 9 is a view similar to Fig. 8 showing a complete impeller vane having suitable means for attaching it in the impeller shroud and web members.

55 Before explaining in detail the present invention it is to be understood that the invention is not limited in its application to the details of construction and arrangement of parts illustrated in

the accompanying drawing, since the invention is capable of other embodiments and of being practiced or carried out in various ways. Also it is to be understood that the phraseology or terminology employed herein is for the purpose of description and not of limitation.

Referring now to Fig. 1, it will be observed that a driving shaft 10 is provided with an impeller housing 11 terminating in a cover plate 12 which has a radially extending portion 13 coaxially arranged relative to a driven shaft 14.

The driven shaft 14 is provided with a turbine hub 15 which carries a second stage turbine web 16 separated from a turbine shroud member 17 by means of second stage turbine vanes 18. The turbine shroud 17 is also provided with first stage turbine vanes 19.

The impeller housing 11 is provided with a plurality of spaced fluid energizing blades 20 interposed between the housing 11 and an impeller shroud 21.

In the operation of the device liquid is transmitted from the second stage turbine vanes 18 to the impeller vanes 20 where it is energized by centrifugal force due to rotation of the impeller housing 11 and the impeller blades 20. The energized liquid is then transmitted to the first stage turbine vanes 19 and is thereafter directed to the second stage turbine vanes 18 to transmit energy through the turbine hub 15 to the driven shaft 14.

A stationary member 22 is concentrically mounted relative to the driven shaft 14. A hub member 23 having external helical threads 24 formed thereon is mounted on the stationary sleeve 22 and is separated therefrom by one-way brake means 25 whereby the hub 23 may rotate freely in one direction but is restrained from rotation in the opposite direction.

A guide wheel hub 26 having internal helical threads 27 is mounted on the external helical threads 24 of the hub 23 in such a manner that it may rotate freely in one direction while being restrained from rotation in the opposite direction by the one-way brake means 25. The guide wheel hub 26 carries a guide wheel web 28 to position a guide wheel channel 29 in the power transmitting fluid circuit preferably between the first and second stage turbine vanes 19 and 18 respectively.

Referring now to Fig. 2, attention is called to the fact that in the formation of the first stage turbine vanes 19 a fluid foil shape of suitable contour is selected. The fluid foil has a center line 30 extending therethrough, and contoured front and rear surfaces 31 and 32 proportioned to absorb energy from a circulating liquid. The shape of the fluid foil section is selected to vary dependent on the speed of the flow of liquid over the vanes and the viscosity of the liquid utilized.

Referring to Fig. 3, it will be observed that the center line 30 of the vane 19 is wrapped around a conical curve such for example as a parabola or hyperbola whereby it has a center line 30b which in one dimension follows the theoretical center line 30a in the first stage turbine. The vane illustrated in Fig. 3 is a two-dimensional vane whereas the vane illustrated in Fig. 1 is a three-dimensional vane. The entrance and discharge angles 33 and 34 are selected in such a manner as to absorb energy from the fluid as efficiently as possible dependent of course on the velocity of fluid flow and the viscosity of the liquid.

Figs. 4 to 6 inclusive illustrate the formation

of the second stage turbine vanes 18 which may be of relatively thin cross section. Referring to Fig. 4, it will be noted that the blades 18 have center lines 40 corresponding generally with the center line 40a of the second stage turbine vanes 18 as illustrated in Fig. 1. These vanes are substantially axial in form and are designed to have working surfaces at the discharge end corresponding generally to the surface of a screw. This working surface may be generated by extending an axis B—B to cut the axis O—O of the turbine. The axis B—B then curves around the axis O—O and moves longitudinally of the device. Towards the end of the vane the turning and moving of the axis B—B is substantially uniform and generates a true screw form as illustrated by the axial positions a—a', b—b' and the distance a—b of Figs. 4 and 5. As the movement progresses the turning and movement of the axis increases and the generated surface approaches that of a screw with non-uniform pitch as illustrated by the positions of the axes c—c', d—d', e—e', etc. which lie on the curve 40a which represents the center of the fluid channel.

Fig. 4 is a two-dimensional view as if the center line 40a of the vane 18 were a straight line, the vanes having inlet and discharge angles as illustrated. Fig. 5 is a side view of the actual three-dimensional vane, and Fig. 6 is a hypothetical view (not a true geometrical view) illustrating the vane as if all the points of the vane were turned in one plane.

Referring now to Figs. 7 to 9 inclusive, it will be observed that the impeller blades 20 are formed by selecting a suitable air foil shape set at a suitable pitch angle 51 relative to the direction of rotation 51a as illustrated in Fig. 7 with a theoretical center line 50 positioned at a suitable angle 51 to the direction of rotation 51a. It will be observed that the center line 50 is substantially straight throughout the major portion of the length of the blade 20 and that it tapers off as illustrated at 52 to reduce the fluid energizing characteristics of the vane and to equalize the fluid pressures in the fluid circuit adjacent the impeller outlet.

Referring to Fig. 8, it will be observed that the air foil shaped impeller blade 20 of Fig. 7 is illustrated in a three-dimensional view in axial perspective as being wrapped around involute curves whereby the shorter portion 53 may be attached to the impeller shroud 21 and the longer portion 54 may be attached to the impeller housing 11. As illustrated, the varying angles of the impeller blade at the web and shroud members blend together.

Fig. 9 illustrates the impeller blade 20 of Fig. 8 wherein pins 55 interconnecting the impeller housing 11 and shroud 21 may be provided to secure the blade against displacement. Stub pins 56 and 57 carried by the blades 20 extend into the shroud 21 and into the impeller housing 11 to additionally anchor the blade.

This is a continuation-in-part of my co-pending application Serial No. 588,163, filed January 22, 1932.

I claim:

1. A blade wheel for a fluid transmission having spaced web and shroud members defining a fluid channel having fluid inlet and exit portions therebetween, fluid energizing three-dimensional blades carried by the blade wheel and having a high pitch angle section adjacent the web and a lower pitch angle section adjacent the shroud, the high and lower pitch angle sections converging

ing intermediate the web and shroud members to provide a fluid foil shaped blade of smooth contour, the exit portion of the blade adjacent the web being curved to embody a lower pitch to decrease its efficiency, and the blade adjacent the shroud being of substantially constant pitch angle section to maintain its efficiency at the exit of the fluid channel.

2. Impeller blades having the character of a fluid foil bent into conformity with a curved center line with larger pitch angle at the web and smaller pitch angle at the shroud, the pitch angle of the blade at the shroud being substantially constant throughout and the pitch angle at the web being relieved adjacent the discharge end of the blade to unify the flow of fluid from radially spaced points of the impeller.

3. Turbine vanes having the character of a fluid foil bent into conformity with a curved center line with larger pitch angle at the web and smaller pitch angle at the shroud, and a small portion of helical form adjacent the trailing edge to reduce the fluid deflecting characteristics of the vanes at the web adjacent the trailing edge of the vanes.

4. A blade wheel for a fluid transmission comprising spaced web and shroud members, a plurality of spaced fluid deflecting vanes interposed between the web and shroud members and defining inlet and outlet portions, each of the vanes being contoured to embody a higher angle pitch section adjacent the web and a lower angle pitch section adjacent the shroud, the pitch angle of the vanes adjacent the web being relieved at

the trailing edges of the vanes to reduce the fluid deflecting characteristics at the exit portion to unify the fluid flow and reduce fluid turbulence.

5. In a fluid transmission a fluid deflecting blade wheel having a web, spaced vanes on the web, each of the vanes embodying a high angle pitch section adjacent the web and a lower angle pitch section spaced from the web, the pitch angle of the vanes being relieved at their trailing edges to decrease the fluid deflecting characteristics of the vanes to reduce fluid turbulence.

6. A blade wheel comprising a web, vanes on the web, each vane having an outer edge of greater arc and higher pitch angle than the arc and pitch angle of the inner edge, and a portion of each vane being contoured adjacent the trailing edge to equalize pressure on the face and back of the vane adjacent the trailing edge thereof.

7. A blade wheel comprising a web, spaced vanes on the web, each vane having an outer edge of greater arc and higher pitch angle than the arc and pitch angle of its inner edge, and a trailing edge of lower pitch angle providing an under-bend for the fluid flow whereby fluid turbulence is avoided.

8. A blade wheel comprising a web, vanes on the web, each vane having a body portion so contoured as to provide for a constant rate of energization of the fluid, and a portion adjacent its trailing edge so contoured as to diminish the rate of energization of the fluid.

JOSEPH JANDASEK.
